COVER CONTROLLED SAFETY SWITCH
MECHANISM FOR POWER OPERATED
TYPEWRITERS OR LIKE MACHINESHenry J. Hart and William H. Kupper, West
Hartford, Conn., assignors to Royal Typewriter
Company, Inc., New York, N. Y., a corporation
of New York

Application September 13, 1949, Serial No. 115,543

9 Claims. (Cl. 197—17)

1

This invention relates to cover controlled safety switch mechanism for power operated typewriters or like machines. Machines of this general class include power operable mechanism comprising numerous parts which are operated rapidly and with considerable force. If, therefore, a foreign object such as a pencil, eraser or other office equipment article should accidentally be dropped into the machine when the latter is operating or is conditioned to operate, the mechanism could be damaged seriously. Moreover, if an operator's finger should be extended inadvertently into the mechanism, for example when changing a ribbon, and the machine should be operated unintentionally, injury could occur. Accordingly it is usual to provide such machines with covers or masks serving to prevent such accidents and injuries, and to protect the working parts from dust.

An object of the present invention is to provide, in a machine of the kind referred to, novel and improved means for so articulating or co-relating a movable cover with a switch controlling the driving motor as to prevent operation of the motor when the cover is opened and the mechanism is not fully or substantially enclosed or masked.

Another object of the invention is to provide articulating or co-relating means of the character stated including a manually operable device operable in a single movement for both moving the cover from open to closed position and for closing the controlling switch to start the driving motor.

A further object of the invention is to provide articulating or controlling means of the kind referred to which is cooperable in a simple manner with a novel and improved signaling mechanism.

Other objects of the invention will become apparent from a reading of the following description of a representative embodiment of the invention, the appended claims, and the accompanying drawings, in which:

Figure 1 is a view, partly in elevation and partly in section, fore and aft of a typewriter embodying the invention, showing only some of the conventional or standard typewriter parts in order to illustrate the application of mechanism embodying the invention to a typewriter construction;

Figure 2 is a fragmentary front elevational view showing a part of a front frame mask panel and a switch operating handle and indicator or signal mechanism, the parts being shown as

2

viewed when looking in the direction of the arrow 2 in Figure 1;

Figure 3 is a fragmentary vertical sectional view showing some of the parts illustrated in Figure 1 in different positions;

Figure 4 is a detail sectional view on the line 4—4 of Figure 2;

Figure 5 is a detail perspective view of an indicator or semaphore signal or flag; and

Figure 6 is a view similar to Figure 5, but showing a modification.

The invention may be embodied in typewriters or like machines of various kinds. For the purposes of illustration it is shown as being applied to a power operated office-type typewriter having, except for switch operating and signaling mechanism to be described, many features in common with the well-known Royal Standard typewriter, and power operating mechanism of the kind disclosed in the copending application of William H. Kupper, Serial No. 6,066, filed February 3, 1948.

The known construction illustrated includes a walled or masked main frame A on which a carriage B equipped with a platen C is mounted for letter-spacing and return movements by means of a top rail 1 on the carriage adapted to roll upon balls 2 which, in turn, are adapted to roll on a frame-mounted bottom rail or track 3. A type-bar segment 4, adapted to be moved to upper and lower case positions by a shifting link 5, serves to mount a set of type bars, one of which is shown at 6 as being pivoted at 7 on the segment 4.

Mechanism for operating the various machine instrumentalities including the type bar 6 may be of the kind disclosed in the Kupper application Serial No. 6,066 referred to above, but, if desired, it may be of any other suitable construction. As shown in Figure 1, a snatch roll 8 of conventional form is adapted to be driven through connections (not shown) by an electric motor indicated diagrammatically at 9. Power for operating the motor is derived from power line connections 10 controlled by a snap switch 11. Key controlled mechanism (not shown) is provided for transmitting power impulses from the snatch roll 8 to a lever, a part of which is indicated at 12 in Figure 1, and thence through a link 13 to the type bar 6. Similar connections may be provided for operating the other type bars and instrumentalities of the machine.

In order to protect the operating parts from dust, and to prevent foreign articles or the operator's fingers from coming in contact with

operating parts, a top cover 14 is mounted on hinge pivots 15, and is urged to its opened position indicated in dotted lines in Figure 1 by a wrap spring 16. The front edge of the cover is formed with a flange 17 adapted, when the cover is closed, to rest on a ledge 18 formed along the upper edge portion of a front mask panel 19 of a frame-mounted mask enclosing the mechanisms carried by the frame. The cover 14 is provided with a keeper 20 adapted to have snap-action engagement with a spring 21 carried by the front mask panel 19, as shown in Figures 2 and 3. Preferably, two such keepers 20 and springs 21 are provided, although only one of each is shown in the accompanying drawings.

In accordance with the invention, improved and conveniently operable mechanism is provided for operating the switch 11, and this mechanism is so co-related to the cover 14 as to assure that the switch 11 always will be constrained to be in "off" position when the cover is open, although the switch may be moved freely to "off" or "on" positions when the cover is in closed position. In the form shown, the switch 11 has a snap-action lever or arm 22, the ball-shaped free end of which is received between spaced upper and lower ears 23 on the rear end of a lever 24 pivoted at 25 on the frame A. The front end of the lever 24 is pivoted at 26 to the lower end of link 27, the upper end of which is pivoted at 28 to one arm 29^a of a three-armed lever 29 pivoted at 30 on the frame A. Another arm 29^b of the lever 29 extends forwardly through a slot 31 in the mask panel 19, and is provided exteriorly of the panel 19 with a finger piece or button 32 which is shaped, as shown in Figure 2, with a narrow right-hand edge 33 adapted to point to or register selectively with markings "off" and "on" on the mask panel 19.

When the lever 29 is in the position shown in full lines in Figure 1, the pointer edge 33 of the button 32 will register with the "on" designation shown in Figure 2. The lever 29, link 27, lever 24 and switch arm 22 will then all be in the positions shown in full lines in Figure 1, so that the switch 11 will be closed, i. e., "on" and the motor 9 will operate to drive the snatch roll 8. In order to stop the motor, the button 32 is raised to the position shown in dotted lines in Figure 1 and in full lines in Figure 3, thus rocking the lever 29 clockwise, and moving the link 27, lever 24, and switch arm 22 to the positions shown in dotted lines in Figure 1, thereby opening the switch and stopping the motor 9.

As previously stated, the mechanism for operating the switch 11 is so coordinated with the cover 14 as to assure that the switch 11 will be closed when the cover 14 is opened. To this end a third arm 29^c of the three-armed lever 29 is equipped with a spring leaf 34 secured to the lever arm 29^c as at 35 and having a pivot pin 36 which is received in an elongated slot 37 in a link 38 pivotally connected at 39 to an ear 40 on the inside of the cover 14.

The pin 36 and slot 37 provide a lost motion connection, so that when the cover 14 is closed, as shown in Figures 1 and 3, the lever 29 can be operated to its "on" and "off" positions without interference by the link 38. Thus when the cover 14 is closed, the connections between the switch 11, the lever 29 and the cover will not interfere with the opening and closing of the switch. However, if the switch should be "on," with the lever 29 correspondingly in the position shown in full

lines in Figure 1, and the cover 14 should then be raised to the dotted line position shown in Figure 1, the link 38 will be moved rearwardly, causing the front end of the link slot 37 to pull the pin 36 rearwardly, thereby rocking the lever 29 to the position shown in dotted lines in Figure 1, the link 27 and lever 24 then being so disposed that the switch arm 22 will be in the "off" position. Thus, if an operator should raise the cover 14, for example to gain access to the ribbon spools, opening of the switch 11 and stopping of the motor 9 will be assured.

After the parts have been moved to the positions shown in dotted lines in Figure 1 with the switch "off" the machine may be reconditioned for operation simply by pressing the button 32 downwardly to its "on" position, causing the switch arm 22 to be moved to close the switch, and simultaneously causing the arm 29^c of the lever 29 to pull the link 38 forwardly and swing the cover 14 downwardly. If, however, it should be desired to close the cover 14 without starting the motor 9, the cover may be moved manually from its open to its closed position without causing any movement of the lever 29 and the connected parts.

The spring leaf 34 may be sprung outwardly from the lever arm 29^c so as to withdraw the pin 36 from the slot 37 of the link 38 if it is necessary, in servicing the machine, to remove the cover 14 from the frame A.

The selective registration of the button 32 with the "off" and "on" designations shown in Figure 2 enables the operator easily to determine when the motor circuit is open or closed. Alternatively, or to emphasize or make available a clearer indication of the condition of the parts, the front panel 19 is formed with a window 41 behind which a semaphore or signal 42 is pivoted on the panel 19 as at 43. The signal 42 includes a flag part 44, the upper half 44^a of which may be of a distinct relatively inconspicuous color, such as gray, and the lower half 44^b of which may be distinctly colored more conspicuously, for example with red substance which preferably is luminous or highly light reflective. The semaphore 42 also has a forked end 45 which receives the arm 29^b of the three-armed lever 29. When the lever is in the "on" position shown in full lines in Figure 1, the conspicuous part 44^b of the semaphore 42 will be disposed immediately behind the window 41. When, however, the button 32 is in the "off" position, the less conspicuous part 44^a of the flag will be disposed behind the window 41. Thus a quick glance at the indicator adjacent the operating button 33 will give a very clear indication of whether the motor is conditioned to run or not.

In the modification shown in Figure 6 a semaphore 46 is similar to the semaphore 42 shown in Figure 5, differing therefrom only in that the flag part 48 shown in Figure 6 is marked conspicuously with the words "off" and "on" in lieu of being surfaced with different colors. The semaphore 46 may be pivoted as at 47 and is formed with a forked end 49 adapted to embrace the lever arm 29^b.

The construction shown embodies the invention in a preferred form, but it is intended that the disclosure be illustrative rather than definitive, the invention being defined in the claims.

We claim:

1. In a power operated typewriter or like machine, a frame; mechanism mounted on said frame; a cover mounted on said frame for movement to open and closed positions; an electric

motor mounted on said frame for operating said mechanism; a switch for controlling said motor; means for operating said switch including a manually operable member mounted on said frame for movements corresponding to "on" and "off" positions of said switch; and a connection between said manually operable member and said cover operable, when said switch is in "on" position and said cover is raised, for operating said member and switch automatically to "off" positions.

2. In a power operated typewriter or like machine, a frame; mechanism mounted on said frame; a mask supported on said frame and substantially enclosing said mechanism and including a cover mounted on said frame for movement to open and closed positions; an electric motor mounted on said frame for operating said mechanism; a switch for controlling said motor; means for operating said switch including a manually operable member mounted on said frame interiorly of said mask for movements corresponding to "on" and "off" positions of said switch and having a part projecting through said mask so as to be accessible for manual operation; and a connection between said manually operable member and said cover operable, when said switch is in "on" position and said cover is raised, for operating said member and switch automatically to "off" positions.

3. In a power operated typewriter or like machine, a frame; mechanism mounted on said frame; a cover mounted on said frame for movement to open and closed positions; an electric motor mounted on said frame for operating said mechanism; a switch for controlling said motor; means for operating said switch including a manually operable member mounted on said frame for movements corresponding to "on" and "off" positions of said switch; and a lost motion connection between said manually operable member and said cover operable, when said switch is in "on" position and said cover is raised, for operating said member and switch automatically to "off" positions, said lost motion connection permitting free movement of said manually operable member to "off" and "on" positions when said cover is closed.

4. In a power operated typewriter or like machine, a frame; mechanism mounted on said frame; a cover member mounted on said frame for movement to open and closed position; an electric motor mounted on said frame for operating said mechanism; a switch for controlling said motor; means for operating said switch including a manually operable member mounted on said frame for movements corresponding to "on" and "off" positions of said switch; and mechanism including a link, a pivotal connection between one end of said link and one of said members, and a pin and slot lost motion connection between the other end of said link and the other of said members, said mechanism permitting free movement of said manually operable member to "off" and "on" positions when said cover member is closed and constraining said manually operable member to be in "off" position when said cover member is opened.

5. In a power operated typewriter or like machine, a frame; mechanism mounted on said frame; a cover mounted on said frame for movement to open and closed positions; an electric motor mounted on said frame for operating said mechanism; a switch for controlling said motor; a three-armed lever pivoted on said frame and

having a first arm extending to a position to be accessible for manual operation; means operatively connecting a second arm of said lever to said switch; a link pivotally connected to said cover; and a pin and slot lost motion connection between said link and the third arm of said lever, said lost motion connection permitting free movement of said lever to positions corresponding to "on" and "off" positions of said switch when said cover is closed but constraining said lever to a position corresponding to the "off" position of said switch when said cover is opened.

6. In a power operated typewriter or like machine, a frame; mechanism mounted on said frame; a mask supported on said frame and substantially enclosing said mechanism and including a top cover; a hinge connection between the rear part of said top cover and said frame; a motor mounted on said frame for operating said mechanism; a switch for controlling said motor; a three-armed lever pivoted on said frame adjacent the front thereof and having a manually operable first arm extending through the front of said mask; means operatively connecting a second arm of said lever to said switch; a link pivotally connected to said cover adjacent said hinge connection; and a pin and slot lost motion connection between said link and the third arm of said lever, said lost motion connection permitting free movement of said lever to positions corresponding to "on" and "off" positions of said switch when said cover is closed but constraining said lever to a position corresponding to the "off" position of said switch when said cover is opened.

7. In a power operated typewriter or like machine, a frame; mechanism mounted on said frame; a mechanism mask supported on said frame and including a front panel formed with a window and a cover mounted on said frame for movement to open and closed positions; an electric motor mounted on said frame for operating said mechanism; a switch for controlling said motor; means for operating said switch including a manually operable member mounted on said frame for movements corresponding to "on" and "off" positions of said switch; a connection between said manually operable member and said cover operable, when said switch is in "on" position and said cover is raised, for operating said member and switch automatically to "off" positions; a flag with distinct surface portions; means mounting said flag inside said front mask panel for movement to position either of said surface portions behind said window; and means connecting said flag to said manually operable member for positioning the flag selectively with an appropriate one of said surface portions behind said window according to the "on" or "off" positions of said member and said switch.

8. In a power operated typewriter or like machine, a frame; mechanism mounted on said frame; a mechanism mask supported on said frame and including a front panel formed with a window and a cover mounted on said frame for movement to open and closed positions; an electric motor mounted on said frame for operating said mechanism; a switch for controlling said motor; means for operating said switch including a manually operable member mounted on said frame for movements corresponding to "on" and "off" positions of said switch; a connection between said manually operable member

and said cover operable, when said switch is in "on" position and said cover is raised, for operating said member and switch automatically to "off" positions; a semaphore signal device having a flag at one of its ends; and means mounting said device on said frame inside said front mask panel to rock about a pivot intermediate the ends of said device, said flag having distinct surface portions, and the other of the ends of said device being forked and engaging said manually operable member so as to be operable thereby to position the flag selectively with an appropriate one of said surface portions behind said window according to the "on" or "off" positions of said member and said switch.

9. In a power operated typewriter or like machine, a frame; mechanism mounted on said frame; a mechanism mask supported on said frame and including a front panel formed with a window and a cover mounted on said frame for movement to open and closed positions; an electric motor mounted on said frame for operating said mechanism; a switch for controlling said motor; means for operating said switch including a manually operable member mounted on said frame for movements corresponding to "on" and "off" positions of said switch; a connection between said manually operable member and

said cover operable, when said switch is in "on" position and said cover is raised, for operating said member and switch automatically to "off" positions; a flag with distinct surface portions, 5 one of which only is luminescent; means mounting said flag inside said front mask panel for movement to position either of said surface portions behind said window; and means connecting said flag to said manually operable member 10 for moving said flag to position the luminescent portion thereof behind said window when said member and switch are moved to "on" positions, and for moving said flag to position the other portion thereof behind said window when said 15 member and switch are moved to "off" positions.
